UNITED STATES PATENT OFFICE.

JOHN ALEXANDER GUINN, OF PERRY, IOWA, ASSIGNOR TO THE RAILWAY AUTOMATIC TIME AND DANGER SIGNAL CO., OF DES MOINES, IOWA.

RAILWAY-SIGNAL.

SPECIFICATION forming part of Letters Patent No. 714,173, dated November 25, 1902.

Application filed March 31, 1902. Serial No. 100,885. (No model.)

To all whom it may concern:

Be it known that I, JOHN ALEXANDER GUINN, a citizen of the United States, residing at Perry, in the county of Dallas and State 5 of Iowa, have invented certain new and useful Improvements in Railway-Signals; and I do hereby declare the following to be a full, clear, and exact description of the invention, such as will enable others skilled in the art to 10 which it appertains to make and use the same.

My invention relates to improvements in railway-signals; and it consists of an attachment employed in connection with the apparatus shown in Letters Patent granted to me 15 and bearing date of May 17, 1892, and numbered 475,108, whereby a train reaching a successive station or a series of stations completes an electrical circuit, so as to operate a signal-arm and a reflector at said station or 20 stations.

Other objects and advantages of the invention will hereinafter appear, and the novel features thereof will be specifically defined by the appended claims.

25 The invention is clearly illustrated in the accompanying drawings, which, with the letters of reference marked thereon, form a part of this specification, and in which—

Figure 1 represents a perspective view of a 30 railway-signal embodying my invention. Fig. 2 represents a vertical central section of a post with attachments, omitting the parts not forming *per se* a part of this invention. Fig. 3 represents a sectional view showing two signaling-posts with electric circuit as embodied 35 in my invention. Fig. 4 represents a plan view of a modification of the invention. Fig. 5 represents a central longitudinal section of mechanism which may be employed in raising 40 the index employed in my invention. Fig. 6 represents a side view of the time or retarding mechanism for lowering the index employed in my invention.

Like letters of reference indicate like parts 45 throughout the several views.

A designates a station or post having an index B guided in a slot C in said post.

D designates a signal arm or block pivoted within said post and having an arm E thereon, 50 which is in the nature of a cam and is adapted

by contact with the index B to be raised so as to pass through the said slot C.

As the arm D is raised to its highest extent the heel F of the same is engaged by the gravity-latch G, which holds it in elevated position, so that it can be readily seen by the engineer on a train passing on the road. Connected with said signal-arm D is a colored glass J'', so located as to be adapted when raised to color the light reflected from the reflector H, or in lieu of said reflector H a lamp may be employed, said reflector or lamp being secured in the casing on the top of the post A.

K designates an electric circuit connected 65 with adjacent posts, a battery L, connected with said circuit, being in each one of the posts and having a ground-wire connected therewith. M designates a movable arm in said circuit adapted to be operated by contact with the lateral projection m of the arm b carried by the index B so as to close the circuit and cause the armature of the magnet N to remove the latch G from contact with the heel F of the signal-arm, thereby permitting 70 the latter to fall and with it the colored glass J''. To raise the said index B, the following-described mechanism may be employed, such, however, being shown, described, and claimed in Letters Patent granted to me May 17, 1892, 75 and numbered 475,108, as hereinbefore mentioned.

D' designates blades of metal each pivoted at one of its ends to a rail and its other end secured to the arm E' of a track F', which 85 rests upon a cross-bar G', upon which the roller F² is guided. To the index B is secured a weighted block W, having a projection X, which is fitted in a vertical groove Y in the post A. A sprocket-chain V is secured 90 at one end to said block and, passing around a sprocket-wheel S, is connected with a cord B², which passes down the post and is secured to the axle G² of the roller F², so as to wind thereon. To retard the falling or lowering 95 of the said index, the following-described mechanism may be employed: In the upper part of the post is located the time mechanism shown in Fig. 6 and which is also shown and described in said before-mentioned Let- 100

ters Patent, said mechanism consisting of the balance-wheel J' , the lever K' , the pallet L' , the escapement-wheel M' , having on its shaft the pinion N' , the gear-wheel P' , meshing 5 with the said pinion, the pinion Q' , meshing with the said gear-wheel P' , the gear-wheel R' , meshing with said pinion Q' , and the sprocket-wheel and the ratchet-wheel T on the shaft of said gear-wheel R' . The ratchet

- 10 T is connected with its shaft T' , so as to rotate therewith; but the sprocket-wheel is loosely mounted on said shaft and carries a gravity or spring-pressed pawl or pawls U , which engages the teeth of said ratchet- 15 wheel, thereby permitting the free movement of the sprocket-wheel on the shaft in one direction and its movement with the shaft in the opposite direction.

As the operation of both the raising and 20 time-lowering mechanism is fully described in said Letters Patent and as said parts are not claimed *per se*, further description of the same is thought unnecessary in this application.

- 25 On the sides of the post is a scale showing minutes.

It will be seen that a train as it passes a station raises the index, signal-arm, and colored glass. As it leaves said station the index 30 begins to lower and the engineer on the next train is able to notice by means of the figures on said post, the time the train ahead is in advance. If the first train has reached the second or succeeding post, which is preferably placed at the two-mile limit, after the 35 last car has passed over the blade that works the signal-tripping lever, so as to complete the circuit at M in that post, and thereby cause the magnet N of the first post to operate the catch G of said post, and release the 40 same from the signal-arm of that post, whereby by the latter, as has been stated before, is permitted to fall, and with it the colored glass J'' .

- 45 When but a single line of track is used, the modification shown in Fig. 3 is employed. In this case two sets of posts, one on each side of the track, are used. Trains going in either direction will operate the index and the signal 50 arm; but the latter would be dropped only by those going one way. For this purpose the following-described mechanism is employed: In the box P , placed adjacent the rail, is mounted a lever Q , having the springs

55 R bearing against it, so as to normally maintain the position shown in full lines in Fig. 4. The electric circuit has a wire from the battery in the post to a contact-point S in said box, and from another contact-point T in said

- 60 box a wire extends to the ground. When the lever Q , which is operated by any suitable projection on the car, is moved in one direction, it closes said contact-points S and T , thereby completing the circuit. A train going in the opposite direction will not operate the lever Q , and therefore the contact or circuit will not be closed until a train passes

the station in the direction of the first one. It will be seen that by this attachment the engineer of a train can be informed not only 70 of the time a former train is in advance, but whether the same has passed the two-mile limit, so that there would be no danger of a fast train running into between stations a slow one on the same track, which feature is 75 of the highest importance in signaling.

From the foregoing it will be seen that I have devised a novel and most efficient form 80 of railway-signal, and while the structural embodiment of the invention as herein disclosed is what I at the present time consider the preferable one it is evident that the same is subject to changes, variations, and modifications without departing from the spirit of the invention or sacrificing any of its advantages, and I therefore do not intend to restrict myself to the details herein disclosed, but reserve the right to make such changes, variations, and modifications as come properly within the scope of the protection prayed. 85

What is claimed as new is—

1. In a railway-signal, a post, a time-index normally extending from said post, and connected with mechanism operated by a passing train so as to be raised, a pivoted signal-arm 95 raised by contact with an arm on said index, and a latch engaging directly with the heel of said signal-arm keeping the same in elevated position, said parts being combined substantially as described. 100

2. In a railway-signal, a post, an index-arm normally projecting from said post, mechanism for rapidly raising said index, a pivoted signal-arm normally housed in said post and raised by contact with said index, a latch engaging directly with the heel of said signal-arm, a reflector on said post, an arm connected with said signal-arm carrying a plate adapted to cover said reflector, and a time-retarding mechanism for controlling the fall 110 of said index, said parts being combined substantially as described.

3. In a railway-signal, a post, an index normally projecting from said post, mechanism connected with said index for rapidly raising 115 the same, a time-retarding mechanism for controlling the fall of said index, a separate pivoted signal-arm adapted to be raised by contact with an arm on said index, a latch engaging directly with the heel of said signal-arm for 120 keeping the same in elevated position, an electric circuit having a magnet in said post adapted to release said latch, contact-points in said circuit and means substantially as described for connecting said contact-points so 125 as to complete said circuit, said parts being combined substantially as described.

4. In a railway-signal, two posts each having an index, mechanism for rapidly raising each of said indexes, and time-retarding 130 mechanism for controlling the fall of each of said indexes, a pivoted signal-arm in one of said posts, a latch adapted to engage directly with the heel of said signal-arm, keeping it

in elevated position, an electric circuit having a magnet in one of said posts adapted to remove said latch from engagement with said signal-arm, and contact-points in the other post adapted to be closed by the raising of the index therein, said parts being combined substantially as described.

5. In a railway-signal, a series of posts, each having an index, and provided with mechanism for rapidly raising the index and a time-retarding mechanism for controlling the lowering thereof, a pivoted signal-arm raised by contact with said index, and electric circuits connected with each two adjacent posts, each 15 circuit having a magnet to release a latch in said post engaging directly with the heel of the signal-arm and holding said signal-arm, and contact-points adapted to be closed by the operation of the index in another post, 20 said parts being combined substantially as described.

6. In railway-signals, a post, an index-arm normally projecting therefrom, mechanism for rapidly raising said index and time-retarding mechanism for lowering the same, a 25 pivoted signal-arm raised by contact with said index, a latch engaging directly with the heel of the signal-arm and holding said signal-arm in elevated position, an electric circuit with a magnet adapted to release said 30

latch, and contact-points to be connected by an arm operated by the raising of said index, said parts being combined substantially as described.

7. In a railway-signal, a time-index, mechanism for raising the same, a separate signal-arm adapted to be raised by contact with said index, a latch engaging directly with the heel of the signal-arm for holding said arm in elevated position, and an electric circuit with a 35 magnet having an armature adapted to release said latch, said parts being combined substantially as described.

8. In railway-signals, a time-index guided in a standard, a signal-arm pivoted in said standard, and adapted to be raised by the movement of said index, a gravity-latch engaging directly with the heel of said arm, a lamp in said standard and a colored glass connected with said signal-arm and adapted to 40 cover said lamp when said arm is raised, said parts being combined substantially as described.

In testimony whereof I affix my signature in presence of two witnesses.

JOHN ALEXANDER GUINN.
